CONCRETE FORM HOLDING MEANS

Samuel S. Colt, Orange, N. J.

Application February 6, 1934, Serial No. 709,942

10 Claims. (Cl. 25—131)

This invention relates to improvements in means for holding the walls of concrete casting forms in operative assembled relation.

In the setting up of forms to receive cast concrete, especially in connection with the production of concrete walls and like structures of specified width, it is desirable to secure opposed form walls in spread or spaced apart relation against both inward and outward displacement. This is usually accomplished by means of transverse tie-rods extending between the form walls, to the ends of which tie-rods are coupled or secured exteriorly projecting bolt rods, which are utilized with suitable holding means to secure externally applied battens and walers in supporting relation to the exterior faces of the form walls. After the concrete material is poured into the form and allowed to set, it is necessary to remove the projecting bolt rods. This is done by disconnecting the inner ends of the same from coupled relation to the tie-rod, and thereupon withdrawing the bolt rods from the hardened concrete. Such operation involves considerable labor, owing to the freezing of the set concrete to the bolt rods, especially where the latter are screw-threaded to engage a coupling means by which attachment thereof to the tie-rod is effected; and not only this, but not infrequently the bolt-rod is broken off, or so bent and distorted during the removing operation, that it cannot be used again, which is undesirable from considerations of economy. To overcome such difficulties, and to provide an arrangement of form wall holding means which is both efficient and economical because the exterior parts and bolt-rods may be easily and quickly removed with a minimum expenditure of time and labor, and without risk of any such injury thereto as will defeat the possibility of their repeated use, is the principal object of this invention. To this end, the present invention provides a removable sleeve adapted to be inserted through the form wall and slidable over the bolt rod so as to cover and protect the interior end of the latter leading to the tie-rod coupling means, thereby shielding the bolt rod from contact with the concrete material poured into the form; said sleeve having an external squared end for application of a twisting wrench thereto when it is desired to loosen the same, and being further provided with means whereby it can be secured to the form wall against displacement, so as to act with the tie-rod and coupling devices in holding opposed form walls spread

against inward collapse, pending the pouring of the concrete material.

The invention has for a further object to provide a novel coupling means cooperative with the tie-rod, bolt rod and protector sleeve, having means for rendering desired wall spacing or spreading operations easy and quick of accomplishment.

Other objects of this invention, not at this time more particularly enumerated, will be understood from the following detailed description of the invention.

Illustrative embodiments of this invention are shown in the accompanying drawing, in which:—

Fig. 1 is a fragmentary vertical cross-section through a form showing the operative form wall holding relations of a tie-rod, bolt rod, coupling device and protector sleeve, these parts being shown in side elevation; Fig. 2 is a similar view, with the protector sleeve and coupling device shown in longitudinal section; Fig. 3 is a similar view, with the protector sleeve in longitudinal section and loosened up preparatory to withdrawal of the bolt rod and dismantling of the form walls; Fig. 4 is a detail transverse section, taken on line 4—4 in Fig. 3; Fig. 5 is a detail transverse section, taken on line 5—5 in Fig. 1; and Fig. 6 is a fragmentary horizontal section through a form, showing a modified construction of protector sleeve.

Similar characters of reference are employed in the hereinabove described views, to indicate corresponding parts.

Referring to the drawing, the reference character 10 indicates a side wall of a concrete casting form, to the exterior face of which are applied, in desired spaced apart relation, the uprights or battens 11. Arranged to extend transversely across the battens 11 are walers 12, which are ordinarily arranged in pairs, the members of which are spaced apart one above the other.

To support the form wall 10, and especially when desired to support the same in spaced or spread apart relation to an opposed similar wall, a transverse tie-rod 13 is employed to extend between such opposed walls. The tie-rod is proportioned in length so as to cooperate with the other elements of the form holding devices in such manner that, when all such elements are operatively assembled therewith, the opposed walls will be spaced and supported in given desired distance apart. The tie-rod ends are threaded as at 14, to enter and engage an internally threaded inner end 15 of a coupler 16.

The coupler 16 is also provided with an outer internally threaded end 17. The coupler is preferably of circular cross-sectional shape, although it may be other cross-sectional shaped if desired. 5 Intermediate its ends, the coupler is provided with a slot or elongated opening 18 forming a peep hole through which may be viewed the entered end of the tie-rod 13. Adjacent to the margins of the opening 18 are suitably inscribed 10 register marks or graduations 19, with which the entered end of the tie-rod 13 may be selectively aligned, as an aid in determining a desired over-all length of tie-rod and couplers as a factor in the attainment of predetermined distances of separation or spread between opposed 15 form walls.

The reference character 20 indicates a bolt-rod having a threaded inner end 21 and a threaded outer end 22. Slidably mounted on the bolt-rod 20 is a protector and spacing sleeve 23. Preferably the sleeve 23 is provided with a tapered or conical inner end 24 of predetermined length, and at the juncture of said conical end with the main body of the sleeve there is provided an 25 external indicating mark 25 adapted to be registered in alignment with the inner face of the form wall 10. The sleeve may also be provided with additional marks 26 spaced outwardly from the mark 25 at various distances corresponding 30 to the thickness of various sizes of form wall material or boards selected for particular forms. These marks 26 are a convenience to the form builder when inserting the sleeve through the form wall from the outside, since by registering 35 a corresponding mark 26 with the outside surface of a form wall, the builder will be assured that the mark 25 registers with the inner surface of such wall, and that the conical end 24 of the sleeve projects into the form the proper distance to cooperate with the overall length of tie-rod and couplers in predetermining the desired distance of separation of an opposed form wall. Formed on the sides of the sleeve are inclined downwardly and inwardly oblique channels or grooves 27. When the sleeve is slid over 40 the bolt rod and through an opening 28 in the form wall 10, so that the conical end of the sleeve is entered within the form interior in operative abutting relation to the coupler 16, nails 29, or staples, may be extended through 45 selected channels or grooves 27 and then driven downwardly into the form wall material, thus holding the sleeve against displacement relative to the form wall, and consequently holding the latter against inward displacement from the desired spaced relation to an opposed form wall, as will be obvious from an inspection of Fig. 1 of the drawing. At or adjacent to its outer end, the sleeve is provided with flat angularly related 50 wrench engageable faces 30, whereby a wrench or other suitable tool may be applied thereto for manipulating the same when it is desired to be loosened from operative position. If desired, the outer end portion of the sleeve may be provided with oppositely extending lateral handle arms 31 to facilitate handling of the same.

It will be observed from an inspection of the drawing, that, when the sleeve 23 is slid inwardly over the bolt-rod 20 into operative relation to the form wall 10 and to the tie-rod 13 and its coupler 16, the sleeve entirely envelops the inner end of the bolt-rod which penetrates the form interior to operatively engage the tie-rod coupler 16, thus protecting or shielding such 70 portion of the bolt-rod from contact with the 75

concrete material, when the latter is poured into the form.

When the bolt-rod and sleeve are operatively related to the form wall 10 and to the tie-rod 13 and its coupler 16, a flanged nut 32, or other suitable fastening device, is engaged with the outer end of the bolt-rod so as to abut the walers 12, thus securely holding the form wall against outward displacement.

In the species of sleeve 23 above described, 10 the same comprises a one-piece substantially cylindrical element. In Fig. 6, however, there is shown a modified species of sleeve which is split longitudinally, as at 33 to provide two cooperating halves 34 and 35, which may be released and withdrawn from the form wall and removed from the bolt-rod before the latter itself is disconnected.

In the use of the novel form holding means, 20 after the concrete material 36 has been poured but before it has fully set to final hard condition, the nails holding the sleeve 23 are withdrawn, and the sleeve is loosened and retracted or, when of split form as shown in Fig. 6, withdrawn. This is done by applying a wrench to 25 the outer end of the sleeve and twisting the same. The sleeve will readily be loosened by such twisting in view of the fact that this may be done while the concrete is still somewhat green. When loosened the sleeve is retracted 30 without disturbing the form supporting relation of the interconnected bolt-rod and tie-rod. After the concrete has aged sufficiently to have become fully hardened (which may be several days after pouring), the bolt-rods 20 may be 35 turned out of the couplers 16 and withdrawn, so that the form walls may be removed. Inasmuch as the sleeves 23 initially protected or shielded the bolt-rods from contact with the concrete material, the same may, at this time, 40 be easily and quickly removed, without risk of distortion, breaking or other injury thereto, and also without risk of injury, chipping or cracking of the concrete. As a consequence of this the bolt-rods may be used over and over again, 45 thus effecting an economy in form building which is very desirable.

Another advantage of the novel form holding means of this invention, lies in the fact 50 that the elements of the same are so constructed and related, that they may be passed through the form walls from the outside thereof when assembling the same, which is of considerable convenience especially in the erection of narrow forms wherein access to the interior is 55 difficult.

I am aware that various changes could be made in the above described constructions, and many apparently widely different embodiments of this invention could be made without departing from the scope thereof as defined in the following claims; hence it is intended that all matter contained in the above description or shown in the accompanying drawing shall be interpreted as illustrative and not in a limiting 60 sense.

I claim:-

1. In concrete form holding means, an internal tie-rod, an exteriorly projecting bolt-rod, a coupler means to join said tie-rod and 70 bolt-rod, and a sleeve loosely slidably over said bolt-rod, said sleeve being adapted to penetrate the form wall from the exterior thereof to cover the inner end portion of said bolt-rod between the form wall and said coupler means.

2. In concrete form holding means, an internal tie-rod, an exteriorly projecting bolt-rod, a coupler means to join said tie-rod and bolt-rod, a sleeve loosely slideable over said bolt-rod, and said sleeve having a tapered inner end portion adapted to penetrate a form wall and abut said coupler means to thereby protect the interiorly disposed portion of said bolt-rod from contact with concrete material poured into said form.
3. In concrete form holding means, an internal tie-rod, an exteriorly projecting bolt-rod, a coupler means to join said tie-rod and bolt-rod, a sleeve loosely slideable over said bolt-rod, said sleeve having a tapered inner end portion adapted to penetrate a form wall and abut said coupler means to thereby protect the interiorly disposed portion of said bolt-rod from contact with concrete material poured into said form, and means to hold said sleeve in predetermined relation to the form wall.
4. In concrete form holding means, an internal tie-rod, an exteriorly projecting bolt-rod, a coupler means to join said tie-rod and bolt-rod, a sleeve loosely slideable over said bolt-rod, said sleeve having a tapered inner end portion adapted to penetrate a form wall and abut said coupler means to thereby protect the interiorly disposed portion of said bolt-rod from contact with concrete material poured into said form, said sleeve having wrench engageable means on its exterior end portion.
5. In concrete form holding means, an internal tie-rod, tie-rod coupler means, a removable bolt-rod adapted to pass through a form wall into attached relation to said tie-rod coupler means, a sleeve loosely slideable over said bolt-rod, said sleeve having a tapered inner end portion adapted to penetrate a form wall to abut said coupler means and cover that portion of the bolt-rod disposed between the form wall and said coupler means, and means to secure said sleeve in affixed predetermined relation to said form wall and cooperatively with said tie-rod and coupler means to dispose the form wall in spaced relation to an opposed wall.
6. In concrete form holding means, an internal tie-rod, tie-rod coupler means, a removable bolt-rod adapted to pass through a form wall into attached relation to said tie-rod coupler means, a sleeve loosely slideable over said bolt-rod, said sleeve having a tapered inner end portion adapted to penetrate a form wall to abut said coupler means and cover that portion of the bolt rod disposed between the form wall and said coupler means, and means to secure said sleeve in affixed predetermined relation to said form wall and cooperatively with said tie-rod and coupler means to dispose the form wall in spaced relation to an opposed wall, said sleeve having external indicating marks registrable with the exterior surface of the penetrated form wall to indicate the desired cooperative relation of the inwardly projecting portion of said sleeve with said tie-rod and coupler means.
7. In concrete form holding means, an internal tie-rod, tie-rod coupler means, said coupler means having an opening in its side and external register marks to facilitate the desired
- positioning of said coupler means relative to said tie-rod, a removable bolt rod adapted to pass through a form wall into attached relation to said tie-rod coupler means, a sleeve loosely slideable over said bolt-rod and through the form wall to abut said coupler means and to cover that portion of the bolt-rod disposed between the form wall and said coupler means, said sleeve being manipulatable from the exterior of the form whereby the same may be loosened from the concrete cast into the form without disturbing the form holding relation of the bolt-rod.
8. In concrete form holding means, an internal tie-rod, tie-rod coupler means, said coupler means having an opening in its side and external register marks to facilitate the desired positioning of said coupler means relative to said tie-rod, a removable bolt-rod adapted to pass through a form wall into attached relation to said tie-rod coupler means, a sleeve loosely slideable over said bolt-rod and through the form wall to abut said coupler means and to cover that portion of the bolt-rod disposed between the form wall and said coupler means, said sleeve being manipulatable from the exterior of the form whereby the same may be loosened from the concrete cast into the form without disturbing the form holding relation of the bolt-rod, and means to secure said sleeve in affixed predetermined relation to said form wall and cooperatively with said tie-rod and coupler means to dispose the form wall in spaced relation to an opposed wall.
9. In concrete form holding means, an internal tie-rod, tie-rod coupler means, said coupler means having an opening in its side and external register marks to facilitate the desired positioning of said coupler means relative to said tie-rod, a removable bolt-rod adapted to pass through a form wall into attached relation to said tie-rod coupler means, a sleeve loosely slideable over said bolt-rod and through the form wall to abut said coupler means and to cover that portion of the bolt-rod disposed between the form wall and said coupler means, said sleeve being manipulatable from the exterior of the form whereby the same may be loosened from the concrete cast into the form without disturbing the form holding relation of the bolt-rod, and means to secure said sleeve in affixed predetermined relation to said form wall and cooperatively with said tie-rod and coupler means to dispose the form wall in spaced relation to an opposed wall, said sleeve having external indicating marks registrable with the exterior surface of the penetrated form wall to indicate the desired cooperative relation of the inwardly projecting portion of said sleeve with said tie-rod and coupler means.
10. In concrete form holding means, retaining members comprising a member wholly within the form interior and a second member extending through the form wall into detachably coupled connection with said interior member, a sleeve loosely slideable over said second member to project through the form wall in covering relation to the interiorly disposed portion of said second member.

SAMUEL S. COLT.
